CLAIM

The ornamental design for a surgical knife, as shown and described.

DESCRIPTION

1., 3. Surgical knives

1.1 : Perspective

1.2 : Front

1.3 : Top

1.4 : Bottom

1.5 : Right

1.6 : Left

1.7 : Enlarged perspective view

1.8 : Enlarged front view

1.9 : Enlarged top view

1.10 : Enlarged bottom view

1.11 : Enlarged left view

3.1 : Perspective

3.2 : Front

3.3 : Top

3.4 : Bottom

3.5 : Right

3.6 : Left

3.7 : Enlarged perspective view

3.8 : Enlarged front view

3.9 : Enlarged top view

3.10 : Enlarged bottom view

3.11 : Enlarged left view
